UNITED STATES PATENT OFFICE.

CHRISTOPHER EDUARD HERTLEIN, OF NEW YORK, N. Y.

DESIGN FOR TRIMMING.

SPECIFICATION forming part of Design No. 23,325, dated June 5, 1894.

Application filed April 26, 1894. Serial No. 509,157. Term of patent 3½ years.

To all whom it may concern:

Be it known that I, CHRISTOPHER EDUARD HERTLEIN, a citizen of the United States, residing in the city, county, and State of New York, have invented and produced a new and original Design for Trimming, of which the following is a specification.

My design consists of a trimming herein shown and described, of essentially the configuration as illustrated in the accompanying drawings, which is an isometric view of a short section of trimming embodying my design.

The essential feature of my design is a se-

ries of shell shaped lobes connected to each other at their edges giving the general effect of a number of shells strung together. 15

In the drawing *a a* represent shell shaped lobes connected together at their edges to give the general effect of a string of shells. 20

What I claim is—

The design for trimming as herein shown and described.

CHRISTOPHER EDUARD HERTLEIN.
